(57) **CLAIM**

The ornamental design for a desktop lamp stand, as shown and described.

DESCRIPTION

FIG. 1 is a front and top perspective view of a desktop lamp stand, showing my, new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the desktop lamp stand in a stretched position;

FIG. 10 is an enlarged view of a portion indicated with 'FIG. 10' in FIG. 1; and,

FIG. 11 is an enlarged view of a portion indicated with 'FIG. 11' in FIG. 1.

The dashed broken lines in the figures illustrate portions of the desktop lamp stand that form no part of the claimed design. The dash dot dash lines in FIGS. 1, 10 and 11 are for the purpose of depicting the cut line of the enlarged view and form no part of the claim.

1 Claim, 11 Drawing Sheets

FIG. 10

FIG. 11
